UNITED STATES PATENT OFFICE.

CHARLES G. GROTNES, OF CHICAGO, ILLINOIS.

EXPANDING MACHINE.

Application filed April 22, 1920. Serial No. 375,702.

To all whom it may concern:

Be it known that I, CHARLES G. GROTNES, a citizen of the United States, residing at Chicago, in the county of Cook and State 5 of Illinois, have invented certain new and useful Improvements in Expanding Machines, of which the following is a specification.

The invention is herein shown as embodied in machinery for forming the rims 10 of vehicle wheels and more specifically in means for bringing such a rim to exact shape and size by deforming the material by outward pressure.

Especially where the rims or parts 15 handled are large and heavy, convenience in handling them is an important factor in the cost of production. Machines having their operating parts mounted on an axis 20 slightly inclined upward from the horizontal, as disclosed in my Patent No. 1,407,- 148, dated Feb. 21, 1922, require a minimum amount of labor on the part of the operator 25 to place the rims in position and remove them again. In a machine of this type, 30 rigidity is an important factor and sometimes a critical consideration as the stresses involved in deforming the material of which a heavy rim is formed are obviously very great.

One object of my invention is to provide a machine for quick and convenient handling of very wide and heavy rims.

Another object is to provide such a machine 35 in which the operating parts are very rigidly supported so that wear is minimized and accurate shapes can be produced.

In the accompanying drawings, Figure 1 40 is a plan view of a machine embodying the principles of my invention. Fig. 2 is an enlarged transverse section through the operating head. Fig. 3 is an enlarged detail of the toggle links. Fig. 4 is a longitudinal section of the operating head and associated parts showing the toggle links on 45 line 4—4 of Fig. 2, and Fig. 5 is a similar view partly in section on line 5—5 of Fig. 2.

The embodiment of my invention selected 50 for illustration comprises a suitable supporting frame 10, a main support or jaw table 11 carried by the frame 10, an outboard support or bearing 13 rigidly supported on the main support, expanding jaws 55 14, and means for transmitting power to the jaws to force them outward.

Each expanding jaw comprises a face portion 16, a bearing foot 17 having a tongue and groove connection at 19 with the main support 11 and an outer bearing having a 60 similar tongue and groove connection at 20 with the outboard bearing 13. As the weight of one of these expanding jaws may easily amount to 150 pounds or so, it will be seen that it must be supported at both 65 ends to be rigid enough to move accurately. A plunger head 22 is adapted to reciprocate inside the expanding jaws 14 and is connected to them by toggle links to force them outward and expand the rim. 70

To further cut down unbalanced twisting force on the jaws and eliminate wear of their guiding surfaces and distortion of the jaws themselves, I provide a plurality of toggle links for each jaw suitably spaced 75 along the jaw so as to receive and resist the contractile force of the rim at points spaced so as to minimize the bending moments in the body of the jaw itself and practically eliminate any torque or twisting action 80 tending to force the jaw out of alignment.

Each toggle link comprises a central portion 23 and spaced perforated ears 25 at both ends. In the space between the ears 25, the bearing surface between the pin and 85 the central portion 23 is slightly less than one-half the periphery of the pin. The ears 25 encircle the bearing pin 26 and provide a smaller bearing surface on the opposite side of the pin. The bearing surface formed in the bearing block 29 carried by the plunger head 22, or in the jaw 14, as the case may be, comprises three spaced 90 bearings (Fig. 2) on one side adapted to take compression from pin 26 and spaced 95 by the ears 25, and two spaced bearing surfaces for the tension at the ends of the pins on either side of the toggle link said bearings being formed by ears 31 projecting from the body of the bearing block or jaw. 100

Upon reference to Fig. 2, it will be seen that a very large part of the entire cross-sectional area of the head is taken up by the jaws, plunger head and toggle links. It is, however, necessary to provide means for supporting the outboard support 13 rigidly. I have illustrated a plurality of spacer blocks 32, approximately egg shaped in cross-section as clearly shown in Fig. 2, abutting at their opposite ends against the surfaces of the main support 11 and the outboard bearing 13. Tension studs 34 enter- 110

ing the body of the main support 11 pass through holes in the spacing blocks 32 and in the outboard bearing 13 and carry nuts 35 which may be tightened down to hold the 5 outboard bearing against the spacing blocks and the spacing blocks against the main support 11. These blocks may be designed, as shown, to occupy almost the entire cross-sectional area not obstructed by the jaws 10 in their movement, or occupied by the links 23 and the plunger head. To prevent accidental rotation of the spacing blocks any suitable means may be provided. I have 15 illustrated in Fig. 5 a small hole 37 in the face of the main bearing and a small projection 38 carried by the spacing block 32 and entering the hole 37.

The plunger head 22 is mounted on the drawbar 40 which is slidably supported in 20 circular bearings in the outboard support and in a sleeve 43 carried by the frame 10 and passing centrally through the main support 11. The outboard support 13 has a sleeve 44 engaging a circular head piece 46 25 mounted on the head 22.

The plunger head 22 itself is slidable on the draw bar 40 and upon inward movement of the draw bar is constrained to move by engagement between its end and the inner 30 face of the draw bar nut 41, which is locked in position by a suitable lock nut 45. Upon outward movement of the plunger to contract the jaws, the plunger head is resiliently held against the drawbar nut 41 by the action 35 of springs 47 coiled around bolts 49 slidable in a ring 50 overlying the head piece 46 and nut 41, said bolts passing through holes in the head piece 46 being threaded into the plunger head. It will be seen that accidental 40 blocking or jamming of the expanding jaws so that they cannot contract will merely compress the springs 47 instead of breaking some part of the machine, which would be the result if there were a positive connection between the plunger head and the plunger. Draw bar nut 41 should preferably be adjusted to move head 22 almost but not quite to dead center. Should the head 22 be carried below the dead center of the links in the 45 expanding stroke by reason of a poor adjustment of the parts 41 and 45, the springs 47 might not be sufficiently powerful to bring the head 22 back through dead center and above it into operating relation. Therefore I prefer to form a shoulder 48 on the draw bar 50 at a point where it will engage the inner end of plunger head 22 at the end of the out stroke and move it back to dead center.

The draw bar has a squared end block 52 55 sliding in guides 53 formed in the frame and is reciprocated by a short bifurcated connecting rod 55 engaging both ends of the pin 56. Any suitable means for rotating the eccentric or crank 58 may be employed. I have illustrated pulleys 59 adapted to receive power

from a belt and supported on a shaft 61 which may drive a large gear 62 on an intermediate shaft 64 through a pinion (not shown). A second pinion 65 on the intermediate shaft 64 drives a large gear 68 to rotate the shaft 70 and the eccentric 58. The frame 10 may have two rearwardly extending spaced flanks to provide bearings for the shafts.

As indicated in Figs. 4 and 5 the axis of 75 the machine is slightly inclined upward from the horizontal, and terminates a suitable distance above the floor level. The advantages of this feature have been fully discussed in my copending application above referred to.

While I have illustrated and described in detail the preferred embodiment of my invention, it should be clearly understood that the disclosure is merely for purposes of illustration, that many modifications and variations will naturally occur to those skilled in the art and that the invention may be embodied in machines for imparting a desired conformation to various classes of annular objects. I aim in the subjoined claims to 85 cover all such legitimate variations and modifications.

I claim as my invention:

1. An expanding machine having, in combination, a main frame, a jaw table secured to the main frame, an outboard support located forwardly of the jaw table, members rigidly securing the outboard support to the jaw table, a circular series of radially movable jaws between the jaw table and the outboard support, each of said jaws having at its rear end an outwardly projecting foot having a tongue-and-groove connection with the jaw table, the forward end of each jaw having a tongue-and-groove connection with the outboard support, the members which secure the outboard support to the jaw table being located within the circle defined by the series of jaws, a drawbar supported in the main frame for movement axially of the series of jaws, a head piece slidably supported in the outboard support, a member secured to the forward end of the drawbar, a plunger head slidable on the drawbar rearwardly of said member and arranged to be moved rearwardly by said member, links connecting said plunger head to said jaws, a ring arranged to be moved forwardly by said member, and means yieldingly connecting the plunger head to the ring for outward movement.

2. An expanding machine having, in combination, a main frame, a jaw table secured to the main frame, an outboard support located forwardly of the jaw table, members rigidly securing the outboard support to the jaw table, a circular series of radially movable jaws between the jaw table and the outboard support, the members which secure the outboard support to the jaw table be-

- ing located within the circle defined by the series of jaws, a drawbar supported for movement axially of the series of jaws, a head piece slidably supported in the outboard support, a plunger head on the drawbar, and links connecting said plunger head to said jaws.
3. In a device of the class described, a circular series of radially slidable jaws, a drawbar reciprocable axially of said circular series of jaws, and an operative connection between said drawbar and said jaws, said connections engaging each of said jaws at a plurality of points.
- 10 4. In a device of the class described, a plunger head reciprocable on an inclined axis, a plurality of radially slidable jaws surrounding the plunger head, a circular series of toggle links connecting each jaw to said plunger head, and means for moving said head.
- 15 5. In a device of the class described, a plunger head, a plurality of radially slidable jaws, a plurality of toggle links connecting each jaw to said plunger head, means for reciprocating said head, and bearings for both ends of said jaws.
- 20 6. In a device of the class described, a plunger head, a plurality of radially slidable jaws, toggle links connecting said jaws to said head, a main support, said jaws being slidably mounted on said main support at one end, and an outboard support supported by said main support and providing sliding bearings for the other ends of said jaws.
- 25 7. In a device of the class described, a main support, an outboard support spaced from said main support, a plurality of radially slidable jaws extending between said supports, and stationary elements in the interstices between said jaws forming a structural connection to support said outboard support from said main support.
- 30 40 8. In a device of the class described, a main support, an outboard support spaced from said main support, a plurality of radially slidable jaws between said supports and having sliding engagement with both of them, a plunger head, toggle links connecting said jaws to said plunger head, and a plurality of stationary elements extending longitudinally in the interstices and clearance spaces between said jaws and toggle links to rigidly support said outboard support from said main support.
- 35 45 9. An expanding machine having, in combination, a main frame, a jaw table secured to the main frame, an outboard support located forwardly of the jaw table, members rigidly securing the outboard support to the jaw table, a circular series of radially movable jaws between the jaw table and the outboard support, each of said jaws having
- 50 55 60 65 65 at its rear end an outwardly projecting foot having a tongue-and-groove connection with the jaw table, the forward end of each jaw having a tongue-and-groove connection with the outboard support, the members which secure the outboard support to the jaw table being located within the circle defined by the series of jaws, and means for moving the jaws.
10. An expanding machine having, in combination, a main frame, a jaw table secured to the main frame, an outboard support located forwardly of the jaw table, a circular series of radially movable jaws between the jaw table and the outboard support, each of said jaws having at its rear end an outwardly projecting foot having a tongue-and-groove connection with the jaw table, the forward end of each jaw having a tongue-and-groove connection with the outboard support, a drawbar supported in the main frame for movement axially of the series of jaws, and means connecting the drawbar to the jaws.
- 70 75 80 85 90 95 100 105 110 115 120 125 130 130
11. In a device of the class described, expanding jaws, positive means for transmitting power to said jaws to expand them, and means having a resilient lost motion connection for transmitting power to said jaws to contract them to the original position.
12. In a device of the class described, radially movable jaws, a reciprocable element having a toggle connection with said jaws, a draw bar for reciprocating said element, means fixedly mounted on said draw bar to engage the face of said element and move it in one direction, and means resiliently supported from said element adapted to engage said moving means to move said element in the opposite direction.
13. In a device of the class described, a draw bar, a nut fixed on said draw bar, a flange at one end of said nut, a head slidable on said draw bar and normally abutting one side of the flange on said nut, and a ring normally abutting the other side of said flange, said ring being resiliently connected to said head.
14. In a device of the class described, a main support and an out board support, a draw bar slidably guided in said main support, a head slidable on said draw bar and having sliding engagement with said out board support, an operative connection for transmitting reciprocating movement from said draw bar to said head, and means for reciprocating said draw bar.
15. In a device of the class described, a main support and an out board support, a draw bar slidably guided in said main support, a head slidable on said draw bar and having sliding engagement with said out board support, an operative connection adapted to act positively in moving said head in one direction and resiliently in

4
moving said head in the other direction for transmitting reciprocating movement from said draw bar to said head, and means for reciprocating said draw bar.

5 16. In a device of the class described, radially movable jaws, a reciprocal element having a toggle connection with said jaws, and means for actuating said element unyieldingly in the direction to move the 10 jaws outwardly and yieldingly in the opposite direction.

15 17. An expanding machine, having, in combination, a main frame, a jaw table secured to the main frame and an outboard support located forwardly of the jaw table, members rigidly securing the outboard support to the jaw table, a circular series of radially movable jaws between the jaw table and the outboard support, the members 20 which secure the outboard support to the jaw table being located within the circle defined by the series of jaws, a drawbar supported in the main frame for movement axially of the series of jaws, and means 25 connecting the drawbar to the jaws.

18. An expanding machine, having, in combination, a main frame, a jaw table secured to the forward side of the main frame, an outboard support located forwardly of 30 the jaw table, members rigidly securing the outboard support to the jaw table, a circular

series of radially movable jaws between the jaw table and the outboard support, the members which secure the outboard support to the jaw table being located within the 35 circle defined by the series of jaws, a drawbar supported in the main frame and in the outboard support for movement axially of the series of jaws, means connecting the drawbar to the jaws, an eccentric rotatably supported in the main frame rearwardly of the jaw table, a connecting rod which connects the eccentric to the drawbar, and means to drive the eccentric.

19. In a machine of the class described, a 45 movable jaw, a reciprocal element having a toggle connection with said jaw, adjustable means for moving said element in the direction to move the jaw outwardly whereby the toggle moves towards dead center and 50 yieldingly in the opposite direction, the actuating means having a part adapted to engage the reciprocal element near the end of the yielding stroke in case of maladjustment of said actuating means, whereby the 55 toggle is forced back to dead center and therefrom yieldingly carried beyond to retract the jaws.

In testimony whereof, I have hereunto set my hand.

CHARLES G. GROTNES.
